UNITED STATES PATENT OFFICE.

HARRY E. KERR, OF CLEVELAND, OHIO, ASSIGNOR TO CLEVELAND GAS BURNER & APPLIANCE CO., OF CLEVELAND, OHIO.

DESIGN FOR A GAS-BURNER.

54,851.

Specification for Design.

Patented Apr. 13, 1920.

Application filed May 26, 1919. Serial No. 299,990. Term of patent 14 years.

To all whom it may concern:

Be it known that I, HARRY E. KERR, a citizen of the United States, residing at Cleveland in the county of Cuyahoga and State of Ohio, have invented a new, original, and ornamental Design for Gas-Burners, of which the following is a specification, reference being had to the accompanying drawing, forming part thereof.

Figure 1 is a top plan view, Fig. 2 a side elevation, and Fig. 3 a bottom view of a gas burner showing my new design.

I claim:

The ornamental design for a gas burner, as shown.

HARRY E. KERR.
